WIDE ANGLE TYPE CATHODE-RAY TUBE
CROSS-REFERENCE TO RELATED APPLICATION

This is a continuation-in-part of the U.S. Patent Application Ser. No. 14,173, filed on Feb. 25, 1970, now abandoned.

BACKGROUND OF THE INVENTION

This invention relates to a cathode-ray tube and more particularly to a wide angle type color cathode-ray tube envelope.

Due to the recent desire to have a television receiving set made more compact and lighter, there has grown demand for a cathode-ray tube enabling electron beams from an electron gun assembly to be deflected at a wider angle than has been possible in the past so as to provide a compact and light color television receiving set. To obtain a cathode-ray tube permitting the wide deflection of electron beams, there are raised problems in connection with the occurrence of the so-called neck shadows at the screen corners and requirement of larger amounts of power to deflect electron beams at a wider angle. The neck shadows originate with the fact that electron beams deflected toward the screen corners are interrupted in their passage by the circular front edge of the cylindrical neck. To avoid the appearance of said neck shadows, electron beams have to be deflected at a limited angle, which in turn has obstructed the development of a cathode-ray tube permitting the wider deflection of electron beams. Further, with the conventional cathode-ray tube using a triple electron gun assembly, beams of electrons emitted from a particular member of said electron gun assembly are liable to be interrupted in their passage at certain corners of the neck portion, obscuring or degrading the color image presented at the corresponding screen corners. Moreover, the neck and conical portions of the prior art cathode-ray tube which are formed with a round cross section present difficulties in properly locating a deflection coil.

As mentioned above, deflection of electron beams at a wider angle requires larger amounts of deflection power, exerting a harmful effect on the other circuits of a television receiving set and further increasing the power consumption of the receiving set as a whole. A cathode-ray tube of wide angle type used to date has a narrow neck to reduce required deflection power. However, such a narrow neck naturally demands that an electron gun to be received therein be made fully narrow, thus giving rise to a blooming effect.

SUMMARY OF THE INVENTION

It is accordingly the object of this invention to provide a cathode-ray tube envelope of the wide angle type which has a rear cone section of rectangular truncated pyramidal shape.

SUMMARY OF THE INVENTION

In a cathode-ray tube of this invention, the conical portion of a funnel-shaped tube envelope which includes tubular neck and conical portions comprises a rear cone section of rectangular truncated pyramidal shape and a front cone flaring therefrom at a wide angle.

The cathode-ray tube envelope of this invention constructed as described above almost fully prevents the

occurrence of neck shadows, enables electron beams to be deflected at a wide angle and moreover permits the easy fitting of the deflection coil at an accurate location.

BRIEF DESCRIPTION OF THE DRAWING

FIG. 1 is a perspective view of a cathode-ray tube according to one embodiment of this invention;

FIG. 2 is a perspective view of a deflection coil;

FIG. 3 is a cross sectional view of a cathode-ray tube fitted with a deflection coil and convergence ring;

FIG. 4 is a cross sectional view of a cathode-ray tube according to another embodiment of the invention with grooves formed along the inside of the ridges defined by the adjacent walls of a rear cone of rectangular pyramidal shape;

FIG. 5 is a cross sectional view on line 5—5 of FIG. 4; and

FIG. 6 is a cross sectional view on line 6—6 of FIG. 4.

DETAILED DESCRIPTION OF THE INVENTION

Referring to FIGS. 1 to 3, a funnel-shaped glass envelope 11 a tubular neck bulb 12 integral with a conical portion 13 widely flaring from the front end of the neck bulb 12. The front side of the envelope is sealed with a faceplate 14 having a rectangular shape, the height of which bears a ratio of three-fourths to the width and coated on the inner surface with a fluorescent screen 15. This fluorescent screen 15 is an ordinary type used with a color cathode-ray tube which is prepared by depositing fluorescent material on the inside of the faceplate 14 in the form of dots constituting triads or triplets, each representing three colors of red, green and blue, or in the form of extremely short strips collectively presenting a different pattern of arrangement in which they are juxtaposed in the specified order of red, green and blue. When excited by scanning electron beams, the aforesaid dots or strips of fluorescent material glow red, green and blue. A shadow mask 16 is so disposed as to face the faceplate 14 at a predetermined distance therefrom. In the neck bulb 12 is received a triple electron gun assembly 17 consisting of three electron gun members arranged in a triangular form or in a straight line.

According to the embodiment of FIGS. 1 to 3, the conical portion 13 comprises a rear cone section 13a of rectangular truncated pyramidal shape which has a rectangular front end and a rear end integral with the neck bulb 12 and a front cone section 13b flaring from the rectangular front end the rear cone section 13a at a wider angle which has a rectangular large front end. The rear cone 13a should preferably have a rectangular cross section similar to the rectangular form of the faceplate 14 so as to resolve the problem of neck shadows.

To the rear end of the neck bulb 12 is attached a stem socket 20 lengthwise penetrated by lead pins electrically connected to the respective electron gun members 18 of the electron gun assembly 17. The electron gun assembly is received in the neck bulb 12 with its top end disposed adjacent to the front side of the neck bulb 12. There is provided an electromagnetic deflection coil 21 so as to surround the rear cone section 13a of the envelope 11. Said deflection coil 21 has its interior formed into a rectangular truncated pyramidal shape similar to that of the rear cone 13a so as to en-

sure a close fit therewith and, as is well known, includes coil members for horizontal and vertical deflection. Around part of the neck bulb 12 is provided a convergence adjusting means 22.

The shadow mask type color cathode-ray tube having the cathode ray tube envelope of the aforesaid construction is not fundamentally different in operation from the ordinary type. Three beams of electrons emitted from the respective members of the triple electron gun assembly 17 have their passage deflected toward the faceplate 14 by the deflection coil 21 to be focused on the predetermined holes of the shadow mask, thereby exciting the corresponding points on the fluorescent screen 15 to reproduce color pictures on the faceplate 14.

According to the cathode-ray tube envelope of this invention, the rear cone 13a is formed, as previously described, into a rectangular truncated pyramidal shape, enabling electron beams from the electron gun assembly 17 to be deflected as widely as, for example, 20 an angle of 110° and more than 110° without being intercepted by the front part of the neck bulb 12, regardless of the direction of said deflection, so that the appearance of neck shadows at the screen corners is eliminated to permit reproduction of true shades of color 25 even at said screen corners.

As mentioned above, the cathode-ray tube having the cathode ray tube envelope of this invention enables electron beams to be deflected at a much wider angle than has been possible with the prior art type, thus 30 prominently reducing the depth and weight of a color television receiving set. Moreover, the rectangular truncated pyramidal shape of the interior of the deflection coil 21 similar to that of the rear cone 13a permits an easy fitting therebetween. Further, insertion of a triple electron gun assembly 17 into the neck bulb 12 in a conformity with the arrangement of the red, green and blue glowing dots or strips of the fluorescent screen 15 can be effected more easily and accurately by taking one side of the rectangular cross section of the rear cone section 13a as a reference side, thereby enabling a cathode-ray tube to display an excellent electrical performance.

There will now be described by reference to FIGS. 4 to 6 a modification of the cathode-ray tube of this invention. According to said modification, the envelope 11 includes, as in the preceding embodiment, a conical portion 13 comprising a front cone section 13b and a rear cone section 13a of rectangular truncated pyramidal shape, and a neck bulb 12. The difference between 45 said modification and the foregoing embodiment is that there are formed four grooves 30 along the inside of the ridges defined by the adjacent walls of the rear cone section 13a. These grooves 30 extend up to the corresponding corners of the rear side of the front cone section 13b with a progressively increasing width and each 50 take a curved form at said corners, with the radius of curvature set at, for example, 2 mm at the front side of the rear cone section.

If the grooves 30 should be formed unduly deep, those parts of the walls of the rear cone section 13a which are adjacent to said grooves 30 would be cracked. To avoid such event, therefore, the grooves 5 30 should preferably be formed to such depth that the aforesaid walls of the rear cone 13a retain at least half the original thickness. Formation of such grooves has the same effect as increasing the transversal dimension of the inner space of the rear cone 13a, thus contributing 10 to minimizing the occurrence of neck shadows.

What we claim is:

1. A cathode ray tube including an envelope comprising:

a tubular neck portion; and
a conical portion including:

a rear cone section of rectangular truncated pyramidal shape over substantially the whole length thereof, said rear cone section having a rectangular front end and a rear end integral with said tubular neck portion, and four grooves extending along the inside of the ridges defined by the adjacent walls of said rear cone section, said grooves extending along substantially the length of said ridges and having a progressively increasing width toward the screen end of the tube; and

a front cone section flaring from the rectangular front end of said rear cone section.

2. A cathode-ray tube according to claim 1 further comprising a deflection coil disposed around said rear cone section and having its interior formed into a rectangular truncated pyramidal shape similar to that of the rear cone section so as to ensure a close fit therewith.

3. A cathode ray tube according to claim 1 further comprising a faceplate fixed to the rectangular wide end of said front cone section; a shadow mask interior of said envelope and facing said faceplate; and a triple electron gun assembly received in said neck portion.

4. A cathode ray tube according to claim 1 wherein 40 at least the front end of each of said grooves is curved.

5. A cathode ray tube envelope comprising:
a tubular neck portion; and
a conical portion including:

a rear cone section of rectangular truncated pyramidal shape over substantially the whole length thereof, said rear cone section having a rectangular front end and a rear end integral with said tubular neck portion, and four grooves extending along the inside of the ridges defined by the adjacent walls of said rear cone section, said grooves extending along substantially the length of said ridges and having a progressively increasing width toward the screen end of the tube; and
a front cone section flaring from the rectangular front end of said rear cone section.

6. A cathode ray tube according to claim 5 wherein 55 at least the front end of each of said grooves is curved.
